DESIGN FOR A DISPLAY PACKAGE FOR A SLIDE FASTENER

Paul T. Poutinen, Manhasset, N. Y., assignor to
Waldes Koh-I-Noor, Inc., Long Island City,
N. Y., a corporation of New York

Application March 27, 1942, Serial No. 106,351

Term of patent 7 years

To all whom it may concern:

Be it known that I, Paul T. Poutinen, a citizen of the United States of America and a resident of Manhasset, Long Island, county of Nassau, State of New York, have invented a new, original, and ornamental Design for a Display Package for a Slide Fastener, of which the following is a specification, reference being had to the accompanying drawing, forming part thereof, wherein:

Fig. 1 is a front plan view of a display package for a slide fastener, showing my new design;

Fig. 2 is a side elevational view; and

Fig. 3 is an end elevational view thereof.

I claim:

The ornamental design for a display package for a slide fastener, substantially as shown.

PAUL T. POUTINEN.
